US00D525379S

(12) **United States Design Patent** (10) **Patent No.:** **US D525,379 S**
Maxik et al. (45) **Date of Patent:** **** Jul. 18, 2006**

(54) **FLASHLIGHT**

(75) Inventors: **Fredric S. Maxik**, Plantation, FL (US);
Catherina G. M. Friderici, Hollywood, FL (US)

(73) Assignee: **Lighting Science Group Corporation**, Dallas, TX (US)

(**) Term: **14 Years**

(21) Appl. No.: **29/224,334**

(22) Filed: **Feb. 28, 2005**

(51) LOC (8) Cl. **26-02**

(52) U.S. Cl. **D26/37**

(58) Field of Classification Search D26/37-50;
362/157, 158, 171-174, 183-208

(57) **CLAIM**

The ornamental design for a flashlight, as shown and described.

DESCRIPTION

FIG. 1 is a perspective view of a flashlight showing our design, with the broken line showing for illustrative purposes only and forming no part of the claimed design.

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is a perspective view similar to FIG. 1 but showing a variation of our design.
